UNITED STATES PATENT OFFICE.

LESTER M. RICH, OF INDIANAPOLIS, INDIANA.

CHICKEN-COOP.

1,029,144.

Specification of Letters Patent. Patented June 11, 1912.

Application filed October 2, 1911. Serial No. 652,330.

To all whom it may concern:

Be it known that I, LESTER M. RICH, a citizen of the United States of America, resident of Indianapolis, county of Marion, 5 State of Indiana, have invented certain new and useful Improvements in Chicken-Coops, of which the following is a specification.

This invention relates to that class of coops in which it is desirable to confine the 10 mother hen and permit the chicks to roam at large, and the special features of the present invention relate to means whereby the chicks and the hen may have access to the feed and water trough from either the 15 interior of the coop or the exterior of the coop, as more fully set forth.

Figure 1, is the perspective view of my improved coop; Fig. 2, a fragmentary sectional view through the water trough; Fig. 20 3, a horizontal sectional view of the coop with the door partly opened; Fig. 4, a vertical sectional view of the coop taken through the feed trough.

In the drawing annexed, *a*, designates the 25 body of the coop which is closed at the top and also at the bottom, the bottom *b* being removable for the purpose of cleaning, since suitable perforations *c* are provided for ventilation purposes, and the side wall of the 30 coop is provided with a large door opening *d*, for egress and ingress of the hen, and also with an adjacent small opening *e* for use of the chicks, the two doorways are adapted to be opened and closed by a door *f*, 35 slidably mounted on the exterior of the coop, and of sufficient extent to close both the openings *d* and *e*. This door is provided with two openings near the floor of the coop, these openings being lettered respectively *f'* and *g*. Attached to the outer face 40 of the door, opposite the opening *f'*, is a water trough *h*, and attached to the door coincident with the opening *g*, is a feed trough *i*, this position of these troughs being 45 such as to permit the chicks to obtain water either from the interior of the coop or the exterior thereof. Attached to the water trough is a water tank *j*, the construction being such that the water shall feed automatically and keep the water at a normal 50 level in the trough. The lower or exit end of the storage tank *j*, is sealed in the water in the trough, entering the water about midway between the inner and outer walls of the 55 trough, so that the hen and the chicks may have access to the trough from the interior

of the coop, as well as the exterior thereof. This trough and its tank are connected rigidly together and slidably mounted in vertical ways *k*, fastened to the exterior of 60 the door, this means of attaching the water supply rendering the same detachable from the door for purposes of cleaning and refilling.

Attached to the feed trough *i*, is the storage box *l*, for the feed, the lower end of the box terminating in the trough, and being so arranged as to automatically deliver the feed by gravity as the same is consumed from the trough. The lower end of this 65 feed box is tapered and arranged to enter the feed trough about midway between its inner and its outer wall, so that the hen and the chicks may readily reach the food in the trough from either the inside or the outside of the coop when the door is closed and the opening *g* is brought opposite the main door opening *d*. This feed box *l* is rigidly attached to the trough, and the 70 whole is mounted removably upon the door 75 by means of vertical guideways *m*, fastened to the door.

It will be observed that the door may be adjusted to confine the hen and yet permit the chicks to pass in and out from the supplementary doorway *e*, and it will also be observed that when the door is closed to confine the hen and the chicks in the coop, access from the interior both to the water and the feed can be had, this being especially desirable in that the hen and the chicks may have food and drink early in the mornings before the attendant has opened the 80 coop.

It will be observed that when the door is 85 closed over both the main opening *d* and the chick opening *e*, the chick opening *e* will permit access to the watering trough. It will be understood that additional openings for ventilation, etc., may be provided. 90 For convenience in filling the feed box *l*, the same is provided with a cover *l'*, and in filling the water tank *j* it is removed from the door and inverted and filled.

What I claim is:

1. A chicken coop provided with a doorway and with a movable door adapted to close the same, this door being provided with two openings adapted to coincide with the door opening when the door is closed, a 100 water trough attached to the exterior of the door coincident with one of the said open-

105

100

110

ings, and a feed trough attached to the door coincident with the other opening.

2. A chicken coop provided with a main large opening and an adjacent smaller opening, in combination with a door slideable over said openings and provided with two openings one of which is adapted to coincide with the aforesaid smaller opening and both of which are adapted to coincide with the main opening, a feed trough attached to the

door and coinciding with one of said openings therein, and a water trough attached to the door over the other opening in the door, for the purposes set forth.

In testimony whereof I hereunto affix my 15
signature in the presence of two witnesses.

LESTER M. RICH.
